HOUSING FOR FOOD MIXER

Alfred W. Wakeman, Box 99, Newtown, Conn.

Filed July 29, 1959, Ser. No. 56,987

Term of patent 14 years

(Cl. D44—1)

FIG. 1

FIG. 2

FIG. 3

FIG. 4

FIG. 5

Fig. 1 is a top plan view of a housing for food mixer showing my new design;
Fig. 2 is a side elevational view;
Fig. 3 is a bottom plan view;
Fig. 4 is a rear elevation view; and
Fig. 5 is a front elevational view.

I claim:

The ornamental design for a housing for food mixer, substantially as shown.
